UNITED STATES PATENT OFFICE

EDUARD MÜNCH, OF LUDWIGSHAFEN-ON-THE-RHINE, GERMANY, ASSIGNOR TO I. G. FARBEININDUSTRIE AKTIENGESELLSCHAFT, OF FRANKFORT-ON-THE-MAIN, GERMANY, A CORPORATION OF GERMANY

PROCESS FOR VAPORIZING FORMAMID

No Drawing. Application filed January 17, 1928, Serial No. 247,461, and in Germany January 27, 1927.

Formamid is difficult to vaporize without decomposition, since it boils at a comparatively high temperature, at which it begins to decompose to a considerable extent, into carbon monoxid and ammonia. Although small quantities may be distilled, almost without decomposition, from glass vessels and under a very high vacuum, similar favorable conditions are generally speaking unattainable in cases where large quantities of formamid vapor are required for industrial purposes.

A further difficulty in carrying out the vaporization on a large scale arises from the fact that, at high temperatures, formamid attacks nearly all metals, so that it is practically impossible to produce suitable heating apparatus for this purpose.

As a result, formamid cannot be successfully vaporized on an industrial scale in the usual manner from stills or similar vaporizing appliances in which the heating surfaces are always covered with the liquid. Even if the apparatus were able to resist the action of the formamid considerable losses of the latter would be incurred by the prolonged heating.

I have found that the decomposition of formamid into carbon monoxid and ammonia, in spite of the fact that this decomposition increases as the temperatures rises, can be almost entirely prevented if the formamid be vaporized on surfaces, heated to a temperature above the boiling point of formamid, which is 215° C. at ordinary pressure, in such a manner that vaporization occurs immediately on contact therewith and that no formamid can accumulate in the liquid form in the vaporizer. The formamid is preferably introduced in a finely distributed condition, for example by injection through a nozzle.

The vaporization may be effected at ordinary pressure, but it is preferably conducted at diminished pressure, and it may be facilitated by the aid of a current of gas. The formamid vapor should be removed from the vaporizer directly it has been formed, and at once led away for the purpose in view, such, for example, as the production of hydrogen cyanid.

Notwithstanding the high temperature, the

formamid does not attack the heating surfaces to more than a slight extent, if at all, under these conditions, since, apparently, a corroding action is exerted by formamid only when in a liquid state.

The vaporizers may be constructed of copper, wrought iron, cast iron or other suitable metals.

In order to maintain the superheated condition, intensive heating is required, the simplest method being to employ a direct flame, though other sources of heat may also be used.

The following example further illustrates the nature of this invention, but the invention is not restricted thereto.

Example

The formamid is injected through a nozzle, and at a velocity corresponding to from 50 to 70 kilograms per hour, into a vessel with a capacity of about 40 litres, heated to about 450° C. by means of powerful gas flames and evacuated to a reduced pressure of about 40 millimetres, mercury gauge, the injection being effected in such a manner that the formamid is uniformly distributed over the heating surfaces and that no accumulation of liquid formamid can take place in the bottom of the vessel. The formamid vapor is carried off at once, for further treatment. The loss of formamid through decomposition into carbon monoxid and ammonia is only about 1 per cent of the original quantity.

If the vaporizer be constructed for example of iron, the resulting formamid vapor may be found to contain hydrogen cyanid which is of advantage when the vapor is to be employed for the production of hydrogen cyanid.

What I claim is:

1. A process for vaporizing formamid which comprises contacting liquid formamid with a surface, heated to a temperature considerably above 215° C., while avoiding accumulation of liquid formamid.

2. A process for vaporizing formamid which comprises contacting liquid formamid in a finely distributed condition with a surface, heated to a temperature considerably

above 215° C., while avoiding accumulation of liquid formamid.

3. A process for vaporizing formamid which comprises contacting liquid formamid together with a current of inert gas with a surface, heated to a temperature considerably above 215° C., while avoiding accumulation of liquid formamid.

10 4. A process for vaporizing formamid which comprises contacting liquid formamid at reduced pressure with a surface, heated to a temperature considerably above 215° C., while avoiding accumulation of liquid formamid.

15 5. A process for vaporizing formamid which comprises injecting liquid formamid onto the inner surface of a closed vessel heated to 450° C. and evacuated to a pressure of 40 millimetres, mercury gauge, while avoiding accumulation of liquid formamid.

20 In testimony whereof I have hereunto set my hand

EDUARD MÜNCH.

DISCLAIMER

1,735,407.—*Eduard Münch*, Ludwigshafen-on-the-Rhine, Germany. PROCESS FOR VAPORIZING FORMAMID. Patent dated November 12, 1929. Disclaimer filed July 5, 1934, by the assignee, *I. G. Farbenindustrie Aktiengesellschaft*.

Enters this disclaimer to certain of the claims of the above identified patent, namely, claims 1, 2, and 3.
